HERNIA TRUSS

Charles H. Rice, Seattle, Wash.

Application March 12, 1946, Serial No. 653,722

4 Claims. (Cl. 128—96)

1

This invention relates to certain new and useful improvements in a hernia truss.

The primary object of the invention is to provide a hernia truss in which the spring bar carrying the pads is so shaped that when placed in position on the body of the wearer and there retained by a flexible or elastic belt strap, the pads are moved both inwardly and upwardly into proper supporting position without discomfiture to the wearer.

A further object of the invention is to provide a hernia truss of the foregoing character wherein the spring bar thereof that carries the hernia pads is of generally sinuous design in front elevation and with downwardly divergent end horns to which a buckled body strap is attached, the general design of the spring bar and its end horns being such that by a pull or strain on the belt the pads carried by the spring bar both move inwardly and upwardly into supporting position with the end horns being freely movable over the hip bones of the wearer without any tendency to binding or digging in activities regardless of the posture assumed by the wearer.

It is a still further and particular object to provide a hernia truss so designed as to assure the pads being held firmly in position solely by the pressure derived from the belt strap, thereby to obviate any need for the employment of the leg-chafing bottom straps which, insofar as I am aware, have been heretofore considered a necessary adjunct of all hernia trusses.

With the above and other objects in view that will become apparent as the nature of the invention is better understood, the same consists in the novel form, combination, and arrangement of parts hereinafter more fully described, shown in the accompanying drawing and claimed.

In the accompanying drawing:

Figure 1 is a front elevational view of a hernia truss constructed in accordance with the present invention and in position on the body of the wearer, the latter being schematically illustrated, and

Figure 2 is a perspective view of the complete hernia truss including the associated belt straps.

The hernia truss includes a spring bar designated in general by the reference character 5 and being of the general design illustrated and of sinuous characteristic includes an upwardly arched center portion 6 merging into downwardly arched adjacent portions 7 that continue in upwardly extending arm portions 8 that are curved downwardly at their outer ends at 9 to terminate in end horns 10 extending at

2

angles generally obtuse to the arm portions 8 and in a slightly outward direction.

The hernia pads are of the usual type, the design thereof being governed by the requirements of the wearer and such pads being adjustably secured to the downwardly arched portions 7 of the spring bar include a metal body having the back or exposed side thereof covered with leather or the like as at 11 while the body engaging face or side thereof is padded and covered by a soft fabric 12 and secured to the back cover as by a line of stitching 13. The pads are adjustably secured to the spring bar by means of screw and washer combinations 14 working through elongated slots 15 formed in the downwardly arched portions 7 of the spring bar.

As illustrated, the end horns 10 are covered by a loop or sleeve 16 formed of leather or like material with the sleeves secured to said horns by means of screws 17 or other suitable fastening devices. A belt is attached to the sleeves 16 on the horns 10, one belt section 18 being secured by stitching 19 or the like to one sleeve 16 being relatively long to extend completely around the back of the wearer and to overlap at its free end a relatively short belt section 20 secured as by stitching at 21 to the other sleeve 16. As illustrated in Figure 2, the free end of the belt section 18 has an attaching wire loop 22 adjustably attached thereto for engagement with a hook (not shown) on the outer side of the short belt section 20. After the truss has been adjusted to the body of the wearer, it is thereafter unnecessary to move the wire loop 22 over the belt section 18, the truss being placed in position on the body of the wearer and removed when desired merely by engaging or disengaging the wire loop from the hook on the short belt section 20.

From the above detailed description of the invention it is believed that the construction and use thereof will at once be apparent, the particular configuration of the spring bar 5 with its end horns 10 being such that when the horns are drawn back by a pull or tension on the belt, the pads automatically move inwardly and upwardly into proper body supporting position. Also, by the particular disposition of the end horns 10 relative to the spring bar 5, the covered horns move freely over the hip bones without discomfiture to the wearer, whether standing or bending over. With an initial adjustment of the belt section 18 as to length, the truss is easily and quickly applied.

It is a particular feature of the present invention

tion that the hernia truss requires no leg straps in order to hold position upon the wearer and maintain proper support for the affected areas of the body, the constant chafing which these bottom straps cause rendering the ordinary hernia truss so uncomfortable that many individuals suffering from hernia conditions refuse to wear the truss after a short period of use and consequently, through lack of support, irritate and enlarge many ruptures which might otherwise heal. The purpose of the leg straps has perforce been one of drawing the truss downwardly. Through the peculiar design of the present truss I am enabled to attain a secure stabilizing of the hernia-support pads without these bottom straps. One structural point of import responsible therefor is that the center portion 6 of my spring bar partakes of an upward curve between the two support pads, and the purpose thereof is to preclude the bar from any liability of coming into contact with the upper anterior crest of the pubis bone, any such contact perforce tending to raise the spring bar as the wearer bends his or her body from the waist such, for example, as in sitting. A second structural point of importance is the particular form and placement of the terminal horns 10. It will be seen from an inspection of Fig. 2 that these horns, when the truss is being worn, lie in sloping planes which might be considered the sides of a right triangular pyramid, and this I accomplish by giving the arm portions 8 a slight twist within their length. The result is to cause the hernia pads to be given somewhat of a compounded motion, a slight rocking action together with an inward pressure, as the horns are drawn rearwardly. When the belt is applied about the waist with the side sections of the belt crossing over the hip area and lodging above the hip bones, the horn-investing ends of the belt must cant downwardly in a slight degree toward the horns, and the line of force transmitted to the horns pulls the pads inwardly and upwardly firmly against the rupture. It is important that the ends of the belt which carry the horn-investing sleeves be integrated with the latter and insure movement of the horns bodily with the belt ends, and as distinguished from any permitted pivotal motion.

While there is herein shown and described the preferred embodiment of the invention, it is nevertheless to be understood that minor changes may be made therein without departing from the spirit and scope of the invention as claimed.

I claim:

1. In a hernia truss of the character described, a spring bar of sinuous formation presenting an upwardly arched portion at the center and in-

verted pad-carrying arches at each side thereof with the end extremities of the bar being turned downwardly to describe terminal horns, a belt strap attached to one of the horns, and a second and complementing belt strap attached by one end to the other horn and of a length normally substantially to overlap the free end of the first-named belt strap when in service, and an adjustable connection between the free ends of said belt straps.

2. In a hernia truss of the character described, a spring bar having an arcuate configuration when viewed from above and, considered in front elevation, presenting an upwardly arched portion at the center and downwardly arched portions at each side thereof and at the end extremities of the bar providing a respective horn extending downwardly and outwardly, hernia pads carried by the downwardly arched portions of said bar at substantially the low extremes thereof, and a belt strap arranged to carry about the back and the sides of the wearer and connecting by the ends with said terminal horns of the bar.

3. In a hernia truss of the character described, a spring bar having an arcuate configuration when viewed from above and, considered in front elevation, presenting an upwardly arched portion at the center and downwardly arched portions at each side thereof and at the end extremities of the bar providing a respective horn extending downwardly and outwardly in planes which describe the sides of a right triangular pyramid, hernia pads carried by the downwardly arched portions of said bar at substantially the low extremes thereof, and a belt strap arranged to carry about the back and the sides of the wearer and connecting by the ends with said terminal horns of the bar.

4. The hernia truss of claim 3 in which the connection from the ends of the belt to the horns comprises, for each said horn, a sheath made an integral part of the belt and closely investing the horn.
